UNITED STATES PATENT OFFICE.

WILLIAM O. BECK, OF CHICAGO, ILLINOIS, ASSIGNOR TO WESTERN ELECTRIC COMPANY, OF CHICAGO, ILLINOIS, A CORPORATION OF ILLINOIS.

AUTOMATIC CALLING DEVICE.

No. 856,386.

Specification of Letters Patent.

Patented June 11, 1907.

Application filed June 4, 1906. Serial No. 320,034.

To all whom it may concern:

Be it known that I, WILLIAM O. BECK, a citizen of the United States, residing at Chicago, in the county of Cook and State of Illinois, have invented a certain new and useful Improvement in Automatic Calling Devices, of which the following is a full, clear, concise, and exact description.

My invention relates to a controller provided with means for setting the same and mechanism for operating the controller when set, said means after setting the controller being rendered inoperative until the controller has completed its operation, so preventing interference by said setting means with the controller after it has been set and during its operation.

My invention is capable of use as an automatic calling device for the substations of automatic telephone exchange systems in order to effect the selective operation of the central office selectors.

My object is to provide an improved device which after being set for operation cannot be tampered with or improperly operated, and so effect an erroneous selection.

My invention as applied to a calling device for automatic telephone systems contemplates a circuit controller such as a circuit-controlling ratchet adapted to be set by manually-operated means, with electromagnetic mechanism adapted to operate said controller after the same is set. The manually-operated means, after setting the controller, are rendered inoperative to affect the controller until said controller has completed its operation.

A feature of the invention consists in the provision of switching mechanism, operated when the manually-operated means are restored to normal condition, and controlling the operation of said electromagnetic mechanism. Said electromagnetic mechanism is adapted to be operated by a pulsating or alternating current in a circuit containing a selector-controlling magnet, said mechanism and magnet operating in synchronism until the controller reaches its normal position, when it opens the said circuit. The controller may be set to different positions according to the number of times it is desired to operate the selector magnet.

I will describe my invention more particularly by reference to the accompanying draw-

ings, which represent the preferred embodiment thereof, and wherein

Figure 1 is a front view of a calling device embodying my invention, showing the numbered dial and indicator arm or lever therefor; Fig. 2 is a view in elevation with the dial plate removed; Fig. 3 is a plan view thereof; Fig. 4 is a view in elevation looking in the opposite direction from Fig. 2; Fig. 5 is a detail view of the setting means for the ratchet, showing the same in an operated position; Fig. 6 is a detail view on line 6-6 of Fig. 3; Fig. 7 is a detail view of the ratchet wheel and its recessed pin for engaging the setting dog or pawl; and Fig. 8 is a simplified circuit illustrating the operation of said calling device.

Like parts are designated by similar letters of reference throughout the several views.

The shaft 1, which is journaled in a post 2 at the rear of the device, and in the face plate 3, carries a circuit-controller or ratchet 4, which is loosely mounted on said shaft, being preferably mounted upon a collar or sleeve 5 surrounding the shaft and carrying an insulating pin 6 adapted when the ratchet is in its normal position to engage a spring 7 and separate the same from its anvil 8. The ratchet when away from normal position is adapted to be returned by a spring 9 surrounding the shaft and connecting said hub or collar 5 with the post 2, the restoration of said ratchet by said spring being under the control of an escapement 10 adapted to be operated by the armature 11 of an electromagnet 12.

Upon the outer surface of the face plate 3 is provided a numbered dial 13, over which an indicator arm or lever 14, provided with a handle 15, is adapted to be manually moved. The lever 14 controls the means for setting the ratchet wheel to a position such that the escapement 10 must be operated by armature 11 a number of times corresponding to the number on the dial to which the indicator is advanced in setting the ratchet, in order to return the ratchet to normal position.

The arm 14 is rigidly secured to the shaft 1, said shaft carrying a pivoted pawl 16 adapted to engage, when the ratchet is in normal position, a pin 17 carried thereby, said pin having a recess 18 in which said pawl is adapted to lock against the tension of a

spring 19 tending to force the pawl against stop 20 upon said shaft. A spring 21 shown in Fig. 2 tends to restore the arm 14 to normal position. Thus normally the pawl 16 locks with the pin 17 of ratchet 4, and when the arm 14 is advanced, said pawl advances the ratchet 4, a number of teeth distant from normal position corresponding to the number to which said arm advances on the dial. The instant, however, the arm is released, the spring 19 throws the dog or pawl 16 against the stop 20, so that in case the handle is manipulated before the ratchet is restored to normal position, such improper operation will be without effect upon the ratchet.

As the lever approaches normal position, a curved tail 22 upon the pawl 16 engages a finger 23 extending upwardly from the base of the structure, and forces the pawl 16 against the tension of spring 19 into position to engage the pin 17 when the ratchet 4 is returned to normal position.

I provide means whereby the escapement cannot be actuated by magnet 12 to operate and restore the ratchet 4 until the crank arm or indicator arm 14 is restored to normal position. The shaft 1 carries an insulating disk 24 adapted when the arm 14 is away from normal position to separate a spring 25 from its anvil 26, said spring when the arm 14 is at its initial position resting in a depression 27 in the periphery of said disk in engagement with its anvil 26. Said contacts 25, 26 control the circuit of magnet 12.

Referring to Fig. 8, which shows a simplified circuit for the calling device, a conductor 28 leads from the free pole of a grounded pulsating or alternating source of current 29, as the case may be, through a selector-controlling magnet 30 to the calling device and thence through magnet 12, contacts 7, 8, and 25, 26, in series, to earth. Now assume the crank arm 14 is moved to number 6 upon the dial, the ratchet 4 will be set forward away from normal position six teeth, the pin 6 being withdrawn from contacts 7, 8, permitting the same to close, contacts 25, 26, however, being separated by insulating disk 24. When the crank arm is released and restored to normal position, springs 25, 26 are brought into engagement and the circuit 28 completed, whereupon waves or impulses of current from generator 29 will traverse the magnet 12, vibrating the armature 11 and operating the escapement 10 to cause spring 9 to rotate ratchet 4 six steps back to normal position, whereupon the pin 6 will separate springs 7, 8, and open the circuit 28. The selector magnet 30 will also receive six impulses and operate synchronously with magnet 12 of the calling device.

I claim:

1. The combination with controlling mechanism, of means adapted to set the same, mechanism for operating said controlling

mechanism after the same is set, and a device for rendering said means inoperative until the operation of said controlling mechanism is completed.

2. The combination with a circuit controller, of manually-operated means adapted to set the same, mechanism for operating said controller after the same is set, and means for rendering said manually-operated setting means inoperative until the operation of said controller is completed.

3. The combination with circuit controlling mechanism, of manually-operated means adapted to set the same, electromagnetic mechanism for operating said controlling mechanism after the same is set, and means, operated as said manually-operated means is withdrawn from said circuit controlling mechanism, for rendering said controlling mechanism inaccessible to said manually-operated means until after the operation of said mechanism.

4. The combination with a circuit controller, of manually-operated means adapted to set the same, electromagnetic mechanism for operating said controller after the same is set, and switching mechanism, operated when said manual means is restored, for rendering operative said electromagnetic mechanism.

5. In an automatic calling device the combination with a circuit controlling ratchet, of a lever and means controlled thereby for setting the ratchet, means actuated after the ratchet is set, to render said lever ineffective to further manipulate the ratchet until the same is restored to its initial position, and means for operating said ratchet and restoring the same to normal position.

6. In an automatic call device, the combination with a circuit-controlling ratchet, of a lever and means controlled thereby for setting the ratchet, means actuated after the ratchet is set, to render said lever ineffective to further manipulate the ratchet until the same is restored to initial position, electromagnetic mechanism for operating said ratchet, and restoring the same to normal position, means for restoring said lever to normal position, and switching mechanism controlling said electromagnetic mechanism, operated by said lever when it reaches normal position.

7. In an automatic calling device, the combination with a circuit-controlling ratchet, of a lever, a pawl operated thereby to set said ratchet, means for withdrawing said pawl from the ratchet after the same is set, means for operating the ratchet, and means for restoring the operative relation of said pawl to the ratchet when said lever and ratchet are restored to initial position.

8. In an automatic calling device, the combination with a circuit-controlling ratchet, of a lever, a pawl operated thereby, a pin on

said ratchet with which said pawl is adapted to engage to set the ratchet, a spring for withdrawing said pawl from said pin when the ratchet is set, means for operating the ratchet after the same is set to restore the same to normal position, and a deflecting finger adapted to engage said pawl when the lever is restored to initial position to move said pawl into position to engage said pin when the ratchet reaches normal position.

9. In an automatic calling device, the combination with a circuit-controlling ratchet, of a lever, a pawl operated thereby to set said ratchet, means for restoring said lever, an electromagnet for operating said ratchet, a circuit for said magnet, a switch controlling said circuit and means for closing said switch operated when said lever is returned to initial position.

10. In an automatic calling device, the combination with a circuit controlling ratchet, of a lever, a pawl operated thereby to set said ratchet, means for withdrawing said pawl after the ratchet is set, a spring for restoring said lever, an electromagnet and a circuit therefor controlling the operation of said ratchet, a switch controlling said circuit, an insulating wheel operated by said lever and adapted while the lever is away from normal position to open said switch and to close the same when the lever is restored, and means for restoring the operative

relation of said pawl to the ratchet when the lever and ratchet are restored to initial position.

11. The combination with a ratchet wheel, of a lever for setting said ratchet, a spring for restoring said lever, a spring for restoring the ratchet, an escapement for said ratchet, an electromagnet and its armature for operating said escapement, a circuit for said magnet, a source of current in said circuit adapted to vibrate the armature of said magnet, and a pair of switches controlling said circuit, one switch being closed when the lever reaches normal position, and the other switch being opened when the ratchet reaches normal position.

12. The combination with a circuit controller, of manually operated means for setting said controller, a device for restoring said manual means independent of the controller, electromagnetic mechanism for operating said controller after the same is set and switching mechanism operated after said manual means is restored, for governing said electromagnetic mechanism.

In witness whereof, I, hereunto subscribe my name this 31st day of May A. D., 1906.

WILLIAM O. BECK.
